CLAIM

The ornamental design for chafing dish frame, as shown and described.

DESCRIPTION

FIG. 1 shows a perspective view of a chafing dish frame;
FIG. 2 shows a front elevation view of the chafing dish frame of FIG. 1;

FIG. 3 shows a right side elevation view of the chafing dish frame of FIG. 1;

FIG. 4 shows a rear elevation view of the chafing dish frame of FIG. 1;

FIG. 5 shows a left side elevation view of the chafing dish frame of FIG. 1;

FIG. 6 shows a top plan view of the chafing dish frame of FIG. 1; and,

FIG. 7 shows a bottom plan view of the chafing dish frame of FIG. 1.

The broken lines are included for the purpose of illustrating portions of the chafing dish frame that form no part of the claimed design.
